UNITED STATES PATENT OFFICE

SANDER DEBUS, OF HASTINGS, NEBRASKA

METALLIC FRAME CONSTRUCTION

Original application filed July 6, 1928, Serial No. 290,769. Divided and this application filed June 5, 1929. Serial No. 368,702.

This application is a division of an application, Serial No. 290,769, filed by me July 6, 1928, the present invention relating particularly to a structure whereby a strong metal frame will be produced and the parts of the frame may be rapidly and easily assembled. The invention is illustrated in the accompanying drawings and will be herein-after fully set forth and particularly defined.

10 In the drawings:

Figure 1 is a front elevation of a portion of a dough-proofing apparatus in which the invention is embodied.

Fig. 2 is an enlarged transverse vertical section of the same,

Fig. 3 is a perspective view of a frame joint,

Fig. 4 is an elevation of the joint,

Fig. 5 is a section on the line 5—5 of Fig. 4,

Fig. 6 is a section on the line 6—6 of Fig. 20 4, and

Fig. 7 is a detail in perspective of a part of the truss shown in Fig. 6.

The dough-proofing apparatus for which the present invention is primarily intended 25 includes a housing built in sections, each section being closed at its front and rear by a door 1 and having a panel 2 over each door.

On the roof of this housing is mounted a casing 3 in spaced relation to the roof and 30 equipped with a door 5 whereby access may be had to the interior of the casing when desired.

A blower casing 6 communicates with the housing 3 at one side of the same through a nozzle or neck 7 and from one side of this 35 fan casing extends an air conduit 9 extending to the ends of the main housing and depending into the same, as shown at 10. At the opposite side of the casing 3, a return air conduit 11 leads from the dough-proofing chambers into said casing 3, as will be understood.

The fan or blower within the casing 6 may be of any approved standard construction and is preferably electrically driven.

In the lower portion of the casing 3, there 45 is provided a water pan or open top tank of

any approved form, indicated at 15, and water to fill this tank is supplied through a water line 16 leading into the casing while an overflow pipe 17 leads therefrom to maintain the water at a substantially uniform 50 level. Above the water pan or receptacle, a steam coil or radiator of any approved form is provided within the casing 3 and indicated, at 18, steam being carried into this coil or radiator through a steam line 19 and carried 55 therefrom through a return steam line 20. A branch pipe 21 extends from the line 19 into the water pan so that steam may be discharged into the water to heat and vaporize the same. Cut-off valves 22 and 23 of any 60 standard or approved construction are provided in the pipes 21 and 19, respectively, so that the flow may be nicely regulated. A humidostat, indicated at 24, is provided in the water pan and so arranged that it will 65 control the action of an ordinary pressure-controlled valve 25 disposed in the pipe 21 and thereby automatically establish or arrest flow of steam into the water according to the conditions within the heating and vaporizing compartment. A thermostat, indicated 70 at 26, is disposed in the upper portion of the dough-proofing compartments and is operatively connected with a pressure-controlled valve 27 so that the flow of steam into the heating chamber may be regulated according to the temperature of the proofing sections.

In the upper portion of each door 1 is a window 30 whereby the condition of the dough in any section or compartment may be 75 noted at any time without opening the door and thereby admitting chilled air to the dough.

The end walls of the housing are preferably constructed of wooden frames and metal 85 sheathing secured thereover, and there are end panels 33 of like construction. There are also inner end walls and the delivery ends 10 of the air conduit extend down between the respective inner and outer end walls and 90

terminate each in a hood from which nozzles 35 project through the inner end wall to deliver warm moist air into the interior of the housing. A ceiling 36 extends between the upper edges of the inner end walls and between the front and rear of the housing. Disposed between the ceiling and the roof 38 is a longitudinal trunk line 39 from which extend a plurality of inlet pipes 40 and 41 having downturned ends opening through the ceiling into the compartments of the main housing, the trunk line 39 being in direct communication with the return conduit 11 whereby the air, after flowing through the housing will be returned to the casing 3.

Each door 1 comprises inner and outer layers or laminations of wood, as indicated at 42 in Fig. 2, metal sheathing 43 and 44 being applied to the faces of the wooden laminations so that a very strong door is produced and the air cannot readily penetrate the same. Channeled strips 45 are arranged around all the edges of the door to impart a neat finish thereto as well as strengthen the same. The doors are hung upon channel bars 47 across the open sides of which flat metal bars or plates 46 are secured, as clearly shown in Figs. 3, 4 and 5, a filler block 48 of wood being disposed within the channel of each bar 47 so as to insure rigidity of the plate 46, and the channel bar extending above the upper end of the plate so as to constitute part of the support for the panels above adjacent doors and also for the roof-supporting trusses which are disposed transversely of the apparatus between the roof and the ceiling. The tops of the door frames are provided by channel bars 49 having their channels presented to the upper end portions of the plates 46 and bolted or riveted to the projecting edges of the latter. Plates 50 are secured to the channels 49 so that their ends abut the side edges of the plates 46 at the upper ends thereof and their longitudinal edges project above and below the respective channels 49, and fillers 51 may be disposed within said channels. Panels 2 are provided over the respective doors and may consist of plates bolted or otherwise rigidly secured to the projecting edges of the plates 50 and to the channels 47. The channel bars 47 are, of course, arranged in upright position at regular intervals and constitute division members between adjacent doors as well as supports for the doors, and the respective channels at the front and rear of the apparatus are transversely alined, as will be understood. Extending between the alined channel bars 47 are trusses consisting of upper and lower T-bars 53 and 54 connected at their mitered ends by vertical T-bars 55 and having struts 56 secured to and extending therebetween at intervals, as will be understood. At the corners defined by the meeting of the bars 55 with the bars 53 and 54

are gusset plates 57 whereby a strong rigid joint is attained. The ends of the trusses fit within the channels of the upper projecting ends of the bars 47 and are riveted into the same while the lower members of the trusses extend across and rest upon the upper ends of the fillers 48 and the plates 46, as will be understood upon reference to Fig. 6. The ceiling 36 is bolted or riveted to the flanges 58 of the lower T-bars 54 and, if it should become necessary to splice the ceiling, girders 59 may be secured to and extend between adjacent T-bars 54 to provide a firm support for the ceiling at the splice. The roof 38 rests upon and is likewise secured to the upper T-bars 53 of the trusses and the roof may consist of wooden laminations 60 and a metal sheathing 61. Angle bars 62 are secured upon all the corners of the structure so as to impart an ornamental finish to the same as well as to reinforce the joints and guard against opening of the same.

Girders 63 are secured to and extend between alined door frames at the front and rear of the housing and brace the structure as well as mark off the several sections, it being understood that the sections or compartments are open to permit circulation of the proofing air.

It will be readily seen that I have provided an exceedingly simple, strong, durable and easily erected apparatus whereby a circulation of warm moist air through several compartments containing dough will be attained and the apparatus may be easily erected in any desired size.

Having thus described the invention, I claim:

1. In a frame structure the combination of upright channel bars, plates secured over the channels of said bars through the lower portions of the same, fillers within the channels of the bars between the same and the plates, horizontally extending channel bars secured to and extending between adjacent plates and upright channel bars, and trusses having their ends secured within the upper projecting end portions of the first-mentioned channel bars at the front and rear of the structure.

2. In a frame structure, a housing consisting of a plurality of sections arranged side by side, uprights between the sections at the front and back of the housing between the sections, doors carried by the uprights to close the front and back of the sections, panels secured to and extending between the upper portions of the uprights above the respective doors, a ceiling supported on the uprights at the lower edges of the panels, and a roof carried by the uprights at the upper edges of the panels.

3. In a frame structure, upright channel bars, plates secured over the channels of the bars and terminating short of the upper ends

thereof, and trusses having their ends secured in the channels of the bars and resting on the upper ends of the plates.

4. In a frame structure, upright channel bars, plates secured over the channels of the bars through the lower portion thereof, laterally extending channel bars secured to projecting edge portions of the plates and abutting the upright channel bars, and plates secured over the channels of said laterally extending bars and abutting the edges of the first-mentioned plates.

In testimony whereof I affix my signature.

SANDER DEBUS. [L.S.]
